UNITED STATES PATENT OFFICE.

HANS VON SCHON, OF PHILADELPHIA, PENNSYLVANIA.

DESIGN FOR A COUPON-BLANK.

SPECIFICATION forming part of Design No. 19,978, dated July 1, 1890.

Application filed April 5, 1890. Serial No. 346,733. Term of patent 7 years.

To all whom it may concern:

Be it known that I, HANS VON SCHON, a citizen of the United States residing at the city of Philadelphia, in the county of Philadelphia and State of Pennsylvania, have invented and designed or produced a new and original Blank for the Coupon of a Credit-Book and other Purposes, of which the following is a specification, reference being had to the accompanying elevational drawing of a blank for such a coupon of my invention, forming part hereof.

The leading features of the blank for such coupon are the two circular figures or rings having a scroll-like ground, and extending across the upper part of the blank from one ring to the other is disposed a curved plain-surfaced or ornamental band. Beneath and between the rings is displayed an escutcheon with a plain-surfaced or ornamental ground, and about midway between the two rings and the curved band and escutcheon is the representation of a bag drawn together by strings or strips. Twigs, limbs, or spears are displayed diagonally from the escutcheon to, in rear, and beyond said rings, and streamers are represented as being displayed around about the lower portion of said rings adjacent to said escutcheon.

Referring now to the accompanying drawing for a further and more detailed description of my design, *a* and *a'* represent the two rings of the blank *A*, having a scroll or other background.

b is the curved band with an ornamental contour and a plain-surfaced background, and extending from the upper part of one ring to that of the other.

c is the escutcheon with a waving contour.

d represents a full bag drawn together by strings or strips *d'*.

e and *e'* are respectively the leaved twigs, limbs, or spears displayed diagonally from the escutcheon *c* to, in rear of, and beyond the rings *a* and *a'*.

f and *f'* are the streamers indiscriminately but artistically displayed around about the rings *a* and *a'*, respectively, and the escutcheon *c*.

The principal characteristic features of my design constituting a blank for the formation of a coupon therefrom I desire it to be understood are the rings *a* and *a'*, the curved band *b*, the bag *d*, and the escutcheon *c*, arranged substantially in the above-described manner.

Having thus described the features of my design, what I claim as new, and desire to secure by Letters Patent, is—

The design for a coupon blank or ornament, as herein shown and described.

In witness whereof I have hereunto set my signature in the presence of two subscribing witnesses.

HANS VON SCHON.
